UNITED STATES PATENT OFFICE.

LLOYD E. ONEAL, OF EAST ORANGE, NEW JERSEY, AND SAMUEL N. MEAD, JR., OF BROOKLYN, NEW YORK, ASSIGNEES TO CHAS. CORY & SON, INCORPORATED, OF NEW YORK, N. Y., A CORPORATION OF NEW YORK.

SIGNALING SYSTEM AND MECHANISM.

Application filed November 13, 1923. Serial No. 674,490.

Our invention relates to signaling systems and mechanism especially available for use in electric power plants such as central stations, although the invention is not limited as to uses and may be adapted for various installations. For the sake of brevity the invention in one exemplifying embodiment will be described as adapted for or installed in a central station, such as a steam turbo-generating station, and this explanation of one adaptation or use of the invention will enable skilled persons to understand its adaptation to other installations or for other purposes, with or without changes or modifications which are within the scope of the appended claims.

The general object of the invention is to enable a switchboard operator or person in charge of operations at a main or "control station" to give definite instructions or orders to engine men or attendants at various places or "operating stations" about the plant, for instance, at various engine room and boiler room stations; to enable the attendant at each station to give a suitable reply signal indicating at the control station the proper execution of the order, and also to enable the attendant at any station to "call" or communicate with the control station and indicate conditions at the operating station or else in effect to request instructions, whereupon the control station operator may give a suitable reply or order to the operating station. A further object is to enable the person at the control station to indicate on a general signal "board" the particular station to which an order is being, or is about to be, given and the particular order given at that station, so that different station attendants may observe the orders on the general signal board and for example, if a particular attendant is away from his station he may thus be informed that his station is being called and will know the nature of the order before he reaches his station to carry it into effect.

The objects, characteristics and advantages of the invention are further sufficiently explained in connection with the following detail description of the accompanying drawings, which show one exemplifying embodiment of the invention. After considering this embodiment, persons skilled in the art will understand that many variations may

be made within the principles of the invention, and we contemplate the employment of any structures or arrangements that are properly within the scope of the appended claims.

Figures 1 and 1^A taken together diagrammatically illustrate a complete signaling system or installation embodying the invention in one form. Figure 1 more particularly represents the main or control station and the general call or signal board, and Figure 1^A shows two of any suitable plurality of operating stations in or about a power station or other "plant" to which the invention may be applicable.

Figure 2 is a front elevation of one suitable form of apparatus for an individual operating station, with certain parts, such as the dial and reply pointer, removed.

Figure 3 is a side elevation of the same with some parts broken away.

Figure 4 is a front elevation of one suitable form of signal apparatus for the main or control station, which may be in general similar to the operating station apparatus with additional parts, as fully explained hereafter.

Figure 5 is a perspective view, from the front, of one suitable form of "general" signal or call board.

Figure 6 is a front elevation of a dial and cooperating signal and reply pointers suitable either for the main station or operating station apparatus.

Figure 7 is an enlarged explanatory diagram of one suitable signaling contact arrangement of the type indicated in Figures 1 and 1^A.

In Figure 1, C designates mechanism or apparatus at a main or control station, G indicates essential features of a general call or signal board, and in Figure 1^A, S¹ and S² represent mechanism or apparatus at two individual stations conveniently designated as "operating stations" in distinction from the main or control station. The system as illustrated in Figures 1 and 1^A is arranged for eight operating stations, two of which are shown. The number of operating stations may vary from one up to any practicable number; many features of the invention are adapted for a system including at least two, and usually a larger plurality of operating stations.

The principal parts of the central or con-

trolling station apparatus, as diagrammatically indicated in Figure 1, are signaling contacts or controlling mechanism A, an indicator motor M, an operating station selector B, 5 a call button D, an "instrument" or "dial" lamp E, a bell F which may be conveniently designated as a call bell, and broadly represents any suitable audible signal for the control station operator, and signal lamps H¹ 10 and H², etc., corresponding to the individual operating stations. These lamps are controlled by relays CR¹, CR², etc. There is also a reset button J, the function of which is later explained. A general signal I which 15 may, in the broader aspect of the invention, be either audible or visual, is represented as a preferred example of a horn of the vibrator or motor-operated diaphragm type, such for instance, as a loud-toned automobile horn. 20 This is represented in connection with the control apparatus, but may be placed at any convenient point about the plant, near the general call board G, or elsewhere. There may, if desired, be two or more of these "general" signals on the same circuit. 25

The principal elements or devices at the general call or signal board G are an indicator motor GM and signal lamps G¹, G², etc. This "general" board may be located at any 30 convenient place, as at an elevated position on a wall, where it may be easily observed from a number of operating stations, or by various attendants from their normal positions about the plant. There may be two or 35 more of the general signals, with their electrical devices in common circuits.

The principal devices or apparatus at each operating station such as S¹ or S⁸, Figure 1^A, are signaling contact mechanism SA 40 controlled by a relay R, an indicator motor SM, the circuits of which and certain other circuits are controlled by a relay R¹, a call button SD, a "dial" or "instrument" lamp SE, a signal lamp SK, and a signal bell SF. 45 Figures 2 and 3 show a representative physical embodiment of one of the operating stations S¹. The physical form of the apparatus may vary greatly, but in the present example it comprises a casing 1, mounted 50 on a pedestal 2 and enclosing the contact mechanism SA, the indicator motor SM, the dial lamp SE and bell SF. The call button SD is mounted in the front wall of the pedestal near casing 1. The "outside" signal lamp 55 SK may be located in any convenient place near the station.

The mechanism at the central or control station C, Figure 4, may be substantially similar, including a similar casing and pedestal 60 1 and 2, with signaling contact mechanism A, indicator motor M, dial lamp E and bell F located in the casing, these parts being similar or identical with parts similarly identified with prefix letter S in the individual 65 station apparatus. Other devices or appa-

ratus peculiar to the control station are added. These additional devices include the relays CR¹, CR², etc., which are conveniently mounted on a panel 3 in casing 1. The upper part of pedestal 2 may be formed into a housing 4, 70 having a removable front cover 5. The selector contacts, diagrammatically represented in Figure 1 in arcuate form or arrangement for illustrative convenience, are preferably 75 actually arranged in circular form and enclosed in casing 4. Contact arm 6, Figure 1, is connected to a hand wheel 7 exposed at the front of housing 4, Figure 4, and a pointer 8 is connected to move with the hand wheel over a suitable dial 9 which may be identified as the "selector dial", suitably marked with numbers to indicate the operating stations and any other suitable indicia including the word "Off" to indicate an "off" or idle position. The lamps H¹, H², etc., of Figure 1 80 are arranged about the dial 9 in positions corresponding to the station numbers. Actually the lamps may be located within the casing behind glasses set in the cover plate 5. The call button D and the reset button J are conveniently located on plate 5. 90

In the control station and operating station apparatus, a dial 10 is located in casing 1 near the front. The dial may be of frosted glass to permit proper illumination by the interior or dial lamp E or SE, or otherwise the dial may be made of opaque material, such as metal, and may be spaced away from the casing at one or more points around its periphery to permit egress of light sufficient to illuminate the face of the dial indirectly after the general fashion of copending application of Frank W. Wood, Serial No. 652,205, filed July 17, 1923. A front or cover glass 11 may be placed in front of the dial 105 and spaced away from it to tightly close the front of the casing. The indicator motor M or SM has its armature shaft 12 provided with a pinion 13 engaging a pinion 14 on a pointer shaft 15 which passes through the 110 dial and carries a pointer 16 in front of the dial, Figure 6. The dial, as is sufficiently exemplified in Figure 6, may be provided with any suitable divisions or legends indicating orders, the orders in the present instance being suitable for a turbo-generator central 115 station. The divisions on the dial may be of uniform spacing, although this is not essential.

The contact mechanism, or control mechanism at each station to effect the positioning of the pointer at another station by the action of the indicator motor at the station last named, that is, contact mechanism A at the control station Figure 4, or mechanism SA at the operating station, Figure 2, has a shaft 17 connected by suitable gearing 18, Figure 3, to a shaft 19 extending through the back wall of casing 1. A lever 20 is secured on the outer end of shaft 19 and this lever is provid- 120 125 130

ed with a handle 21 and a forward extension 22, bearing a pointer 23 which moves over the outer portion of dial 10.

The general signal board, Figure 5, may consist of a suitable box or casing 24 having a dial 25 on its front face, spaced off and marked to agree with the central and operating station dials. An indicator motor which may be in physical form like the motors M 10 or SM, Figures 2 or 4, is enclosed in the housing and its armature or a shaft 26 connected with the armature bears a pointer 27 moving over the dial face. The front face of the housing also has apertures L¹, L², etc., which 15 may be provided with glasses suitably numbered to agree with the operating station numbers, and lamps G¹, G², etc., Figure 1, are located behind these glasses.

The general manner of operating the system may now be understood. The control station attendant, desiring to give an order to a particular operating station, such as stations S¹, rotates the hand knob 7, Figure 4, moving the pointer 8 from off position to numeral 1 on dial 9. By contacts and circuit arrangements hereafter described, whenever the pointer is moved away from off position and in line with any of the operating station numbers on dial 9, the contact or indicator motor control mechanism A at the control station is energized or thrown into circuit, the indicator motor M at the control station is similarly energized or placed in circuit, and the contact mechanism SA and indicator SM at the particular station indicated by pointer 8 are also similarly energized or thrown into circuit; for instance, in the present case, the contact mechanism SA and motor SM at station S¹ are energized. At the same time, the dial lamp E at the control station, the dial lamp SE at the operating station and the outside signal lamp SH at any convenient place near the operating station or on a machine such as the turbine or 45 dynamo at that station, are illuminated. When a general signal or signal board G, Figures 1 and 5, is provided, the act of positioning the selector pointer 8 causes the illumination of appropriate lamp G¹ and 50 therefore the illumination of the appropriately numbered aperture or window on the signal board, visible throughout the engine room or similar plant-section, and the indicator motor GM of the general signal is also 55 energized or thrown into circuit with contact mechanism A at the control station.

The indicator motors are of such type or construction that their armatures move in accordance with the positioning of the shaft 60 of the corresponding contact mechanism. Accordingly, when the selector handle 7 was moved to throw a particular operating station into circuit, the pointer 16 at that station under the control of contacts at the control station immediately moved to a position cor-

responding to the momentary position of handle 21 and its pointer 23 at the control station. To insure giving a correct signal at the operating station at the moment that it is thrown into circuit, the handle 21 at the control station may be positioned to give the desired order before pointer 8 is moved to the station number on the selector dial 9. Pointer 16 at the operating station therefore instantly assuming the same position as the pointer 23 75 at the control station; the attendant at the operating station executes the order and then moves handle 21 at his station, which may be referred to in this connection as a reply controlling device, to the same section of the 80 dial. Contact mechanism SA at the operating station thereupon controls indicator motor M at the control station in such a way that pointer 16 at the control station moves to the same dial position in which handle 21 85 rests at the control station, indicating a compliance with or completion of the order. While the selector remains in the same position, any other order may be given by moving handle 21 at the control station. Contacts included in the contact mechanism A are preferably provided of such nature that whenever central station handle 21 is moved from one dial position to another, bell SF at the operating station rings, so that the attendant's attention is forcibly called by audible signal to the fact that a new order is being given. The new order may now be 90 executed and reply made to the control station in the same fashion.

The control or central operator may at any time reposition the selector pointer to bring any other operating station in circuit and transmit orders to it, and when through with operations for the time being may return the pointer to off position, thus throwing the entire system, except certain "call" 95 circuits, substantially out of circuit.

The horn or other general signal I is provided as a general "attention" call, and it may be operated at any time, usually before an order is given, or especially an important order, by the central station operator pressing the call button D, whereupon the horn is thrown in circuit and "all hands" look at the general board to note the station and order given, or else pay attention to their particular station indicator to see what is wanted.

The system also provides facility for any operating station attendant to communicate with the control station. The attendant at any station, such as station S¹, Figure 1, in order to call the central station operator, presses the call button SD. This closes the circuit of bell F at the control station and also closes the circuit of the appropriate lamp H¹; the central station operator's attention is thus attracted both by audible and visual signals, and the visual signal informs him which sta- 120 125 130

tion is calling. When the attendant at the operating station releases his call button the bell circuit is broken, but lamp H¹ preferably remains in circuit after the call button is released and until its circuit is broken by the central station operator pressing the reset button J. To respond to the call the central station operator sets pointer 8 on number "one" of dial 9, this action being almost 10 voluntary, since he has only to bring the pointer opposite the lighted lamp. This setting of the pointer establishes the circuits between the particular operating station and the control station, or in other words, energizes the respective contact devices and indicator motors. The station attendant may have previously set his pointer 23 by moving his handle 21, this now serving as the signaling element instead of a reply element, 15 as in the previous instance, to bring the pointer on the proper dial space, or he may move handle 21 after "calling" the central operator.

Appropriate indication is thereupon given 25 at the central station by pointer 16 and is answered by the central operator moving his handle 21 to the desired dial space which may be in agreement with the position of pointer 16 or may be some other space to give the desired instruction to the attendant at the operating station. At any time after the central operator sets his pointer at the proper station mark on the dial 9, he may push the reset button J to extinguish the lamp, such 30 as H¹, or he may defer this action until his business with the particular operating station is completed. The circuits of bell F are so arranged preferably, that so long as connection is effective between the central 35 station and an operating station, any movement of handle 21 at the operating station from one position to another causes the bell to ring and thus forcibly attracts the attention of the central operator to the fact that 40 a new signal or inquiry is being made.

The particular electrical devices employed 45 may vary greatly in the broader aspect of the invention. We have referred to contact mechanism A or SA to control the respective indicator motors. The invention is not limited to the employment of contact mechanism for this purpose since in some cases synchronous alternating electric machines might be employed at the respective stations. In 50 the present embodiment of the invention, however, which is more particularly designed for the use of direct current, the contact mechanism and corresponding indicator motors may be of the type set forth in United 55 States Patent to Frank W. Wood, No. 1,216,533, February 20, 1917. The nature of contact mechanism A or SA is sufficiently explained in Figure 7. It includes suitably insulated stationary contact rings 30 and 31 60 which are connected to opposite sides of the

line when the contact mechanism is in circuit. Adjacent to these rings is a circular series of spaced bell ringing contacts 32 connected by conductors 33. The ring of contacts so formed has a connection to one side 70 of the line. Adjacent to the other contacts is a circular series of spaced and insulated indicator-motor-controlling contacts or segments 35^a, 35^b, 35^c, 35^d, and 35^e. Connected to move with the shaft 17 (which in turn is 75 connected to handle 21 as previously described) are contacts or brushes 36, 37 and 38, all electrically connected and relatively arranged substantially as shown, so that brush 36 is always in contact with continuous 80 contact ring 31 and contacts 37 and 38 are equally spaced at opposite sides of contact 36 and arranged to move in contact with indicator-controlling segments 35^a, 35^b, etc. The brush group 36, 37 and 38 is shown in one 85 signaling position, and in all such positions brush 36 is located on an insulated segment or on a space between two adjacent bell ringing contacts 32, and the bell circuit controlled by the contact mechanism is therefore broken; 90 but when the brush system is moved to another signaling position, brush 36 sweeps over one or more of the contacts 32 and the bell is rung during that movement for purposes previously described. Another brush 95 system consists of moving contacts or brushes 30, 41 and 42, all electrically connected and connected to move with shaft 17, the position of this brush system being diametrically opposite to the other brush system, and the brushes 41 and 42 being equally spaced at opposite sides of the radial line of brush 40. Brush 40 moves always in contact with circular contact ring 30, and brushes 41 and 42 move over indicator-motor-controlling 100 contacts 3^a, 3^b, etc.

The arrangement and spacing of brushes 37, 38, 41 and 42 in relation to the spacing of contacts 35^a, 35^b, etc., is such, as sufficiently explained in the above mentioned Patent No. 1,216,533, that in every position of the brushes one or more certain coils of the corresponding indicator motor are properly energized to position the motor armature, and therefore to position the corresponding pointer 16, on a 110 definite dial space, which for convenience, naturally corresponds exactly to the position of the signaling pointer 23 connected to move with contact shaft 17.

To cooperate with contact mechanism such 115 as described, each indicator motor M, SM and GM, includes an armature mounted on the corresponding armature shaft 12 previously mentioned, and provided with a winding 44. Equally spaced around the armature 120 are field coils 45^a, 45^b, 45^c, and 45^e, similar ends of all these coils being connected to a common conductor 46 and the other similar ends, shown for convenience as outer ends, 125 connected to individual conductors as fur- 130

ther particularly described. The armature coil 44 is energized whenever the indicator motor is in circuit and field coils 45^a, 45^b, etc., are energized singly or in different groups or arrangements, depending on the position of the brushes of the corresponding contact mechanism, Figure 7. The particular arrangement here shown is such, as further explained in detail in the patent above mentioned, that the armature assumes an angular position corresponding to that of the diametral line 17^a, Figure 7, which is the center line of the contact-mechanism brush system. Therefore, whenever the shaft and connected brushes of any contact mechanism are stationary, the armature of the corresponding indicator motor is stationary, holding its pointer in a position corresponding to the pointer which is connected to move with the contact controlling shaft 17, and whenever the contact shaft is moved by moving its handle 21, the corresponding indicator motor pointer moves accordingly.

A suitable circuit arrangement will now be described in detail with reference to Figures 1 and 1A.

Positive and negative system main wires 50 and 51 are connected to outside main wires 52 and 53, supplying current of suitable voltage, such as 120 volts "direct," by a double-pole switch 54 and suitable fuses 55. Positive main wire 50 is connected by branch wires 56 to similar ends of solenoids 57 of relays CR¹, CR², etc. An extension 58 of positive wire 50 goes to one binding post of bell F. A wire 59 goes from the other binding post of the bell to all the operating stations S¹, S², etc., and at each station a branch 60 runs to a fixed contact 61 adjacent to a contact 62 operating with a movable metallic arm 63, which is operated by the call button SD at the station. Negative main wire 51 of the system is branched at 65. One conductor 66 goes from 65 to all the stations and at each station a branch wire 67 is connected with the movable metallic contact 63 just mentioned. When the call button at the station is pressed, therefore, the circuit of call bell F at the control station is closed between contact 61 and

wire 67, and the bell rings as long as the button is held down. Cooperating with the wires 67 at the respective stations, are wires a¹, a²...a^s running to contact segments c¹, c²...c^s of the station selector. Moving contact arm 6 previously mentioned runs over the contacts c¹, c², etc., which for convenience in Figure 1, are shown as an arcuate development of the usual circular arrangement in which one insulated or dead segment c⁰ is provided, this being duplicated in the diagrammatic view, and corresponding to the "off" position at which pointer 8 is located in Figure 4.

Contact arm 6 is connected to positive wire 58 by a conductor 68. At each operating station various electrical devices are connected

across wires 67, and a¹, a², etc. Thus lamps SK and SE are connected between the wires; solenoid 70 of relay R is connected by wires 71 and 72; armature coil 44 of indicator motor SM is connected by wires 73 and 74; and solenoid 75 of relay R' is connected by wires 76 and 77. A conductor 78 also goes from each wire a¹, a², etc., to contact ring 30 of the corresponding contact mechanism SA and a conductor 79 goes from each wire 67 to contact ring 31 of the corresponding mechanism. From contacts 62 of the respective operating stations, wires b¹, b²...b^s go to the control station, where branches from these wires are connected to terminals of corresponding solenoids 57 of the relays CR¹, CR², etc., completing circuits through the solenoids and wires 56 previously mentioned to positive line wire 50, whenever the corresponding call button SD is pressed.

The armatures of relays CR¹, CR², etc., have contacts 80 cooperating with fixed contacts 82 and 83. The lamps H¹, H², etc., are connected to the wires b¹, b², etc., each of which leads to one of the fixed contacts 82, and from the other fixed contact 83 a wire 84 is connected to a wire 85 common to the station-indicating lamp system. This wire connects to a wire 86 branched from the negative line wire 51 at 65, and spaced contacts 88 are interposed in wire 85 and normally bridged by a metal contact 89 controlled by the reset button J.

In all positions except the off position, contact arm 6 bears on a continuous contact sector 90, and a wire 91 runs from this sector to positive contact ring 30 of control station contact mechanism A. The wire 86 previously mentioned, which is of opposite polarity, runs to negative contact ring 31. The horn I or equivalent general signal is connected across wires 58 and 86 by wires 92 and 93, and the contacts of general call button D are interposed in one of these wires, such as 92. Instrument or dial lamp E is connected across wires 86 and 91 by wire 95 and a branch from wire 93. Armature 44 of motor M is connected across wires 86 and 91 by wires 97 and 98.

While relays R and R' at the operating stations may be of any known or suitable type, they are represented for convenience as having armatures 100 pivoted at 101. The armature of each relay R carries insulated contacts cooperating with fixed contacts 102^a, 102^b...102^s which are wired to contact segments 35^a, 35^b, etc., of contact mechanism SA, the correspondence of relay contacts and contact segments being indicated by similarity of the suffix letters. The armature contacts are connected to wires 105^a, 105^b...105^s which run to the outer ends of field coils 45^a, 45^b...45^s of indicator motor M at the control station, so that similarly located segments of all the contact mechanisms at the

operating stations are connected or may be connected when the appropriate relay contacts are closed, to similarly located field coils of indicator motor M, as clearly indicated by the similar lateral suffixes of the reference numerals. A branch 110 is taken from wire 59 previously mentioned, leading from bell F to a contact on the movable armature of each relay R, this contact corresponding to a fixed contact 111 which is wired to the annular series of bell ringing contact segments 32 of contact mechanism SA.

The armature 100 of each operating station relay R' carries insulated contacts cooperating with fixed contacts 115^b, 115^c, 115^d and 115^e corresponding to field coils 45^b, 45^c, 45^d, and 45^e, respectively of indicator motor SM and wired to the outer ends of those coils, and the corresponding movable contacts are connected to wires 120^b, 120^c, 120^d and 120^e. Coil 45^a may be connected to a similar wire 120^a by a continuous conductor 121 without a contact break, since the field coil circuit is normally open at all of the contacts 115^b . . . 115^d. The wires 120^a . . . 120^e are common to all the operating stations and run to contact segments 35^a, 35^b, etc., of contact mechanism A at the control station, so that each contact segment is connected to a similarly located field coil at any operating station, whenever the armature or relay R' is moved to close the contacts 115^a, 115^b, etc., the actual circuit connections, of course, depending on the momentary position of the brushes 36, 37, 38, 40, 41 and 42 as sufficiently explained in connection with Figure 7. The connection of field coils to similar contact segments, and the appropriate relay contacts, can be easily traced by similarity of the literal suffixes to the reference numerals.

The armature 100 of each relay R' also carries an insulated contact cooperating with a fixed contact 125 which is the terminal of a wire 126 connected to wire 74 previously mentioned, and bell SF at the corresponding operating station is interposed in this wire 126. All of the armature contacts corresponding to the fixed contacts 125 are connected to a common wire 130, which runs to the annular series of bell ringing contact segments 32 of control station contact mechanism A.

The field coils of the indicator motor GM of the general signal G are connected to appropriate wires 120^a, 120^b, etc., the connections being sufficiently indicated by similarity of the literal suffixes of the reference numerals. One end of armature coil 44 of the motor GM is connected by a wire 135 to continuous contact sector 90 of the selector switch mechanism and the other end of the armature coil is connected to a common wire 140 leading from the negative main 51 at the point 65. Branches are taken off of wire 140 to all of the general indicator lamps G¹, G²,

etc., and from these lamps connections are made to wires a¹, a², . . . a^s, etc., the appropriate connections being easily traced by similarity of the numeral suffixes to the reference letters.

When selector contact arm 6 is in "off" position central station contact mechanism A, instrument lamp E, and armature coil 44 of indicator motor M are disconnected, armature 44 of general indicator motor GM is disconnected, and lamps G¹, G², etc., are dead, their circuits being interrupted between contact sector 90 and the contact arm; but when arm 6 is on any contact segment c¹, c², etc., the stated elements are in circuit, that is to say, contact rings 30 and 31 of the contact mechanism, and armature 44 of the motor are energized and ready to perform their operative functions, and lamp E is illuminated, armature 44 of general indicator motor GM is energized and one of the lamps G¹, G², etc., of the general signal board is illuminated, this lamp corresponding to the particular contact segment c¹, c², etc. When selector contact arm 6 is on any one of the segments c¹, c², etc., say c¹, lamps SK and SE, contact rings 30 and 31 of contact mechanism SA and armature coil 44 of motor SN at station S¹ are "connected" or energized, solenoid 70 of relay R is energized, moving the relay armature and closing all of the contacts 102^a . . . 102^e, thus placing contact segments 35^a . . . 35^e of contact mechanism SA in operative relation with corresponding field coils 45^a . . . 45^e of motor M at the control station through wires 105^a . . . 105^e, and contacts 111 are closed, placing the bell-ringing contact segments 32 of contact mechanism SA in circuit with bell F at the control station through wire 59; solenoid 75 of relay R¹ is energized, moving the relay armature 100 to close all of the contacts 115^b . . . 115^e, thus placing the field coils 45^a . . . 45^e of indicator motor SM at the particular operating stations in operative relation, with corresponding contact segments 35^a . . . 35^e of contact mechanism A and in parallel relation to the field coils of general indicator motor GM; contacts 125 are closed, placing bell SF at the operating station in circuit with bell-ringing contact segments 32 of contact mechanism A. When contact arm 6 is on any other of the contact segments all of the stated devices at station S¹ are de-energized or disconnected, and when the contact arm is in "off" position the stated devices of all the operating stations are dead or disconnected.

Regardless of the position of the selector contact arm the circuit of the general call or attention signal I is always complete except for the break at the contacts controlled by the call button D; the circuit of signal bell F at the control station is always complete except for the interruption at contacts 61 and 63 controlled by the operating station

call button SD; and the circuits of solenoids 57 of relays CR¹ CR², etc., are always complete except for the break between contacts 62 and 63 controlled by the operating station call buttons. The central station operator therefore may sound the general signal I at any time by pressing call button D, and the attendants at any of the operating stations may signal the central station by means of lamps H¹, H², etc., at any time by pressing their call buttons SD, and at the same time bell F is rung as long as the button is pushed, to audibly attract the attention of the central station operator. When the call button at any operating station such as S¹ is pushed the circuit of bell F is closed between contacts 61 and 63. The bell circuit is sufficiently clear from previous explanation. The circuit of the corresponding solenoid 57 is closed by the contacts 62 and 63, this circuit being from positive line 50 through the solenoid of relay CR¹ to wire b¹, through the contacts 62 and 63 to wire 67, to wire 66, to negative line 51. The solenoid attracts its armature and the circuit of the corresponding lamp H¹ is closed, this circuit being from the positive line through the solenoid and a part of wire b¹ to the lamp, to contact 82, to contact 80, to contact 83, to wire 85, through the movable contact 89 of the reset button J to wire 86, to negative line 51. When the call button SD is released, bell F stops ringing, but the lamp remains lighted by reason of its established circuit through the solenoid until the lamp circuit is cleared by the central station operator pushing the reset button, which breaks the lamp circuit between contacts 88.

When the central station is "called" in the stated manner the operator moves selector contact arm 6 to contact c¹, c², etc., corresponding to the station calling, or to one of them if more than one station calls simultaneously; or if the signaling operation originates with the central operator in absence of an operating station "call", he moves contact arm 6 to any desired contact, such as c¹. Thereupon the central station devices or apparatus, the general signal devices and the devices or apparatus at the particular operating station S¹ are connected or energized as previously described. The signaling operations are then conducted in a manner also described above. It will be sufficient to describe the circuits for one signaling operation. When the central operator moves his handle 21 from any dial position to another, brush 36 of contact mechanism A moves over at least one bell-ringing contact segment 32, and bell SF at the operating station rings to attract the attendant's attention, the bell circuit being from positive line 50 to wire 58, to wire 68, to contact arm 6, to contact c¹, to wire a¹, to wire 73 through armature coil 44, to wire 74, to the bell, to wire 126, to contact 125, to wire 130, to the bell ringing contacts

32, to brush 36, to negative ring 31, to wire 86, to negative line 51. When handle 21 is brought to rest with pointer 23 in a signaling position, for instance, the one indicated in Figure 6, brush 36 is on a space or insulated segment between two contacts 32, and the bell circuit is broken. The circuit of armature 44 of indicator motor SM has been sufficiently explained. The armature coil is always energized and is attracted to a definite position by energizing the field coils 45^a, 45^b, etc., one at a time, or in different combinations. When the pointer 23 at the control station is in the position of Figure 6 the circuit is from positive ring 30 of contact mechanism A to brush 40, to brushes 41 and 42, which in this instance both rest on contact segment 35^a, to wire 120^a, to contact 115^a, to field coil 45^d, of indicator motor SM, to conductor 46, and from negative ring 31 of contact mechanism A to brush 36, to brushes 37 and 38, to contact segments 35^a and 35^b, to wires 120^a and 120^b, to wire 121, through coil 45^a of the indicator motor to the common conductor 46 and from wire 120^b to contact 115^b through coil 45^b to the common conductor 46. Field coils 45^a, 45^b and 45^d are thus energized, and the energized armature coil is so attracted that pointer 16 at station S¹ moves to the position shown in Figure 6, that is, to the same position on the operating station dial that the pointer 23 rests on at the control station. In any other position of contact mechanism A, one or more different field coils of the indicator motor SM are energized as sufficiently explained in the above mentioned Patent No. 1,216,533, and thus the pointer 16 at the operating station may be moved to any of the dial positions.

After the order is executed the attendant at the operating station moves his handle 21 to the dial space corresponding to the position of pointer 16. The brush system of contact mechanism SA at station S¹ is thus brought to a position identical with that of contact mechanism A, as shown in Figure 7, and field coils 45^a, 45^b and 45^d of the indicator motor M at the control station are energized, the circuits being from positive ring 30 of contact mechanism SA to brush 40, to brushes 41 and 42, to segment 35^a, to contact 102^a, to wire 105^a, to coil 45^d, to common coil conductor 46 of motor M, and from negative contact ring 31 to brush 36, to brush 37, to contact segment 35^a, to contact 102^a, to wire 105^a, to coil 45^a of motor M, to common conductor 46, and from brush 36 to brush 38, to segment 35^b, to contact 102^b, to wire 105^b, to coil 45^b, to common coil conductor 46. The pointer 16 at the control station is thus brought to the same position as the signaling pointer 23, indicating to the attendant there the completion of the order at the operating station.

The armature of motor GM at the general

signal board of course moves in synchronism with the armature of motor SM at any operating station which is in circuit, or is in other words, controlled by the contact mechanism A; and the appropriate lamp G¹, G², at the general board is also illuminated, so that attendants throughout a large part of the plant or factory may by looking at the general board know which station is being 10 signaled and what the order is at that station.

What we claim is:

1. A signaling system comprising a control station, a plurality of operating stations, 15 means at the control station for selectively connecting the operating stations with the control station, means for selectively transmitting different definite visual signals to and fro between the control station and 20 the selected operating station, a general signal station, means thereat for indicating the selected operating station to which a signal is being transmitted from the control station, and means whereby the indicating 25 means is selectively operated in response to the selecting operation of the central station selective connecting means.

2. A signaling system comprising a control station, a plurality of operating stations, 30 means for selectively connecting the operating stations with the control station, means for selectively transmitting different definite usual signals to and fro between the control station, and the selected operating 35 station, a general signal station, means there-

at for indicating a particular signal transmitted from the control station to any operating station, means also at the general station for indicating the selected operating station to which a signal is being transmitted 40 from the control station, means whereby the signal indicating means is selectively operated in response to the operation of the selective transmitting means, and means whereby the station indicating means is selectively 45 operated in response to the operation of the selective connecting means.

3. A signaling system comprising a control station and thereat an operating station call indicator including individual indicator lamps corresponding to individual operating stations, a plurality of operating stations, a call circuit from each operating station to the corresponding individual indicator lamp, means at each operating station for closing its 55 call circuit, cooperative visual signaling and indicating mechanisms designed for selectively giving different definite visual indications at the control and operating stations, circuits therefor, and means at the control station for controlling the last named circuits to selectively connect the control and operating stations for mutual signaling operations.

Signed at New York, in the county of 65 New York and State of New York this 26th day of October, A. D. 1923.
